Specification of Letters Patent. Patented May 22, 1917.

Application filed June 8, 1914. Serial No. 843,686.

To all whom it may concern:

Be it known that I, ARNOLD A. WEIGEL, a citizen of the United States, and a resident of Chicago, in the county of Cook and State 5 of Illinois, have invented certain new and useful Improvements in Antifriction-Bearings; and I do hereby declare that the following is a full, clear, and exact description thereof, reference being had to the accompanying drawings, and to the letters of reference marked thereon, which form a part of this specification.

This invention relates to improvements in antifriction bearings and consists of the matters hereinafter described and more particularly pointed out in the appended claims.

The antifriction bearing, as shown herein, is designed especially for use as a side bearing to be interposed between the car bolster 20 and truck bolster of a railway car, and as illustrated, is embodied in a form wherein it is to be applied or attached to the truck bolster. The invention, however, involves several features which are applicable not 25 alone to a construction in which the bearing is attached to the truck bolster but also to one in which the bearing is attached to the body bolster of a truck.

The many advantages of my invention and 30 the broad application of its various features will appear more clearly as I proceed with my specification.

In the drawings:—

Figure 1 is a view representing the longitudinal central section through a side bearing of a railroad car applied to the truck bolster thereof and embodying the various features of my invention.

Fig. 2 is a view similar to Fig. 1, with the 40 antifriction elements of the bearing shown in a position when rocked from the center.

Fig. 3 is a view representing a horizontal section through Fig. 1 in a plane indicated by the line 3—3 thereof.

Fig. 4 represents an end elevation of the bearing, as illustrated in Fig. 2.

Fig. 5 is a view representing a vertical section through Fig. 1 in a plane indicated by the line 5—5 thereof.

Fig. 6 is a perspective view of the casing of the bearing with part of one wall broken away to show the inner construction.

Fig. 7 is a perspective view of one of the antifriction elements.

Fig. 8 is a perspective view of one of the 55 followers used in the embodiment of the invention shown in the drawings.

Referring now to that embodiment of my invention illustrated in the drawings, 10 indicates the casing which contains the antifriction elements of the bearing and which, as shown herein, is attached to the truck bolster 11 of a railroad car. 12 indicates the body bolster of the car. Said body bolster is usually protected in the part to be engaged by the antifriction elements of the bearing with a wear plate in a familiar manner.

The antifriction casing, as shown herein, contains two antifriction elements, 13, 13, but 70 it will, of course, be understood that said antifriction bearing may include any number of antifriction elements, depending upon the load to be transmitted between the car body bolster and the truck bolster. Said 75 antifriction elements are segments of cylinders and have top and bottom cylindric bearing surfaces 13^a, 13^b, respectively, and rest, in the embodiment of the invention illustrated, upon the bottom of the casing. 80

The casing 10 has upright side walls 14, 14, end walls 15, 15 and a bottom wall 16. The bottom wall of the casing which rests upon the body of the truck bolster and receives the downward thrust of the antifriction elements, is preferably protected by 85 means of the wear plate 17.

The end walls 15, 15 of the casing are provided with recessed bosses 18, 18. 19 indicates a rod extending longitudinally through 90 the casing and fixed at its ends in the end walls 18^a, 18^b of said bosses. The bosses 18, 18^b are preferably reinforced in their connection with the casing 10 by means of ribs 18^b, 18^b. 95

The antifriction elements 13, 13 are each provided with a transversely extending slot 20, through which the rod 19 extends. Said slots have sufficient width (see Fig. 3) to provide free play between the rod 19 and the 100 side walls 21 of said slots. The slots are placed symmetrically with reference to the horizontal central axes of the antifriction elements and each slot has top and bottom walls 22, 22, which diverge in either direction from the central vertical diameter of the antifriction elements in order to prevent 105 said top and bottom walls from striking the

rod when the antifriction element is oscillated through its full amplitude of movement.

23 indicates that side of the antifriction 5 element which is next to and adapted to contact with the adjacent antifriction element. Said side is curved inwardly toward the vertical central axial plane of the antifriction element from the lines in which the top and 10 bottom bearing surfaces of said element terminate, as shown at 23^a, 23^b in such manner that as the adjacent element rocks, the like line of said adjacent element will ride upon, without binding against the said side, as 15 clearly illustrated in Figs. 1 and 2. By providing an intermediate reverse curve of the same radius as indicated at 23^b, when the antifriction elements have been rocked through the full amplitude of their intended 20 movement, the side of one will engage and lock against the side of the other, (see Fig. 2,) thus limiting and preventing further movement of the two elements.

In order to determine the curvature of 25 that side of each rocking antifriction element which is next to the adjacent element, the length of the arc of the bearing surface, that is to say the arc through which the antifriction element is intended to rock is 30 first determined. Then with the ends of said arc and the height of the antifriction element fixed and the form of the proximate sides still undetermined, the two elements are constructed in successive positions which 35 they occupy as they are rocked on one or the other of their bearing surfaces. The successive points occupied by the end of the bearing arc of the one element are then noted, as it is intended that the points thus 40 successively marked off are to define the proximate surface of the adjacent antifriction element, the ordinates defining each of said points with reference to the vertical diameter of the adjacent antifriction element in the successive corresponding positions 45 which it occupies, are carefully measured:—that is to say, the ordinate representing the distance from each of said points to the vertical diameter of the antifriction element and the ordinate representing the distance from the point where said first-named ordinate intersects said diameter and the center of the antifriction element. These 50 ordinates are then laid off on a figure defining the height and the top and bottom bearing surfaces of an antifriction element of the intended size. The curve passing through said points is then drawn, the last point corresponding to the full rocking 55 movement of the antifriction element. Such a curve is laid off in connection with both the top and bottom bearing surfaces, and the two curves thus defined are connected by a curve of the same radius. Manifestly, when the antifriction elements are 60 65

constructed with the sides defined in this way, the interacting relation between the two elements heretofore described, will result.

In addition to this locking feature of the antifriction element, each end antifriction element of the series is provided adjacent that bearing surface 13^b which engages the wear plate of the casing in which it is contained, with laterally spaced extensions or lugs 24 which have bearing surfaces 24^a that are tangential to the bearing surface 13^b of said element in the rocking movement of the series of elements. Manifestly, when the set of antifriction elements are rocked toward one end of the casing, the flat bearing surfaces 24^a of said lugs will engage against the wear plate and prevent further rolling, rocking movement of the end antifriction element, and it, in turn, will prevent the further rocking movement of the other antifriction elements. In addition, the lugs 24 are provided with upright bearing surfaces 24^b at right angles to the bearing surface 24^a which are adapted to engage the upright end wall of the casing when said antifriction elements have been rocked to the limit of their movement.

To provide for the return of the antifriction elements to a normal upright position in the center of the casing, I provide the following:—25, 25 indicate followers adapted for engagement with the end antifriction elements of the series in the casing. Said followers consist of channeled blocks which embrace the rod 19, and which have apertured ends 26 through which said rod extends. The other ends of said blocks are provided with upright shoulders 27 which engage depending shoulders 28 at the inner 100 ends of the bosses 18 of the casing to limit the movement of said blocks 25 toward the center of the casing. 29 indicates expansion coiled springs mounted on the rod 19 and adapted to act between the end walls 110 18^a of the bosses and the ends 26 of the blocks 25. The said end walls of the bosses have suitably formed slots 27^a (see Fig. 4) to permit the passage through said walls of the blocks 25 when in the rocking movement of the series of antifriction elements, said blocks are required to move beyond the limit of the casing.

Manifestly from this construction, the springs cause the followers 25 to yieldingly 120 engage the end antifriction elements in such manner that when the series of antifriction elements have been rocked from central position the springs will cause the follower at that end of the casing toward which the 125 antifriction elements have been rocked to return said antifriction elements to their normal position. The ends 26 of the followers have rounded bearing surfaces 26^a for engagement with the proximate side of the 130

end antifriction element which is rounded as indicated at 26^b so as to provide a friction bearing between the followers and the anti-friction elements with which they engage.

5 I claim as my invention:

1. An anti-friction bearing comprising a casing, a plurality of closely spaced anti-friction rockers in said casing having top and bottom bearing surfaces of a length adapted to provide for a predetermined amplitude of rocking movement of said rockers, each of said rockers having that side, which is adjacent to the next rocker, curved inwardly from the terminal lines of its bearing surfaces toward its vertical, diametric plane, and having an intermediate, joining, reversed-curved surface of the same radius whereby said rockers may rock in engaging relation through substantially the full predetermined amplitude of their rocking movement.

2. An antifriction bearing comprising a casing, a plurality of closely spaced anti-friction rockers located in said casing and having top and bottom bearing surfaces of a length adapted to permit a rocking movement through a predetermined angle, each of said rockers having that side, which is adjacent to the next rocker, curved inwardly from the terminal lines of its bearing surfaces toward its vertical, diametric plane, and having an intermediate, joining, reversed-curved surface of the same radius whereby said elements are permitted to rock together through substantially the full angle determined by their bearing surfaces, but which are adapted to lock said elements against further rocking movement when the limit of said angle of rocking movement is reached.

3. An antifriction bearing comprising a casing, a plurality of closely spaced anti-friction elements located in said casing and having top and bottom bearing surfaces of a length adapted to permit a rocking movement through a predetermined angle, each of said rockers having that side which is adjacent to the next rocker, curved inwardly from the terminal lines of its bearing surface toward its vertical, diametric plane, and having an intermediate, joining, reversed-curved surface of the same radius, whereby the side of one element may bear against the proximate side of the adjacent element throughout a rocking movement through the full angle determined by the length of their bearing surfaces.

4. An antifriction bearing comprising a casing, a plurality of closely spaced anti-friction rockers located in said casing and having top and bottom bearing surfaces of a length adapted to permit rocking movement through a predetermined angle, each of said rockers having that side which is adjacent to the next rocker, curved inwardly

from the terminal lines of its bearing surface toward its vertical, diametric plane, and having an intermediate, joining, reversed-curved surface of the same radius, whereby the side of one element may bear against the proximate side of the adjacent element throughout a rocking movement through the full angle determined by the length of their bearing surfaces and acts to stop the further movement of said element when the same has been rocked through its predetermined limit of movement. 70

5. An antifriction bearing comprising a casing, a plurality of closely spaced rocking antifriction elements located in said casing and having top and bottom bearing surfaces of a length adapted to permit a rocking movement through a predetermined angle, each of said rockers having that side which is adjacent to the next rocker, curved inwardly from the terminal lines of its bearing surface toward its vertical, diametric plane, and having an intermediate, joining, reversed-curved surface of the same radius, whereby the side of one element may bear against the proximate side of the adjacent element throughout a rocking movement through the full angle determined by the length of their bearing surfaces, and means for returning said antifriction element to a vertical position when released. 80

6. An antifriction bearing comprising a casing, a plurality of closely spaced antifriction rockers located in said casing and having top and bottom bearing surfaces of a length adapted to permit rocking movement through a predetermined angle, each of said rockers having that side which is adjacent to the next rocker, curved inwardly from the terminal lines of its bearing surface toward its vertical, diametric plane, and having an intermediate, joining, reversed-curved surface of the same radius, whereby the side of one element may bear against the proximate side of the adjacent element throughout the full angle of rocking movement, determined by the length of their bearing surfaces, and acts to stop the further movement of said element when the same has been rocked through its predetermined limit of movement, and means for returning said antifriction elements to a vertical position when released. 100

7. An antifriction bearing comprising a casing, a plurality of closely spaced rocking antifriction elements located in said casing and having top and bottom bearing surfaces of a length to permit of a rocking movement through a predetermined angle, each of said rockers having that side which is adjacent to the next rocker, curved inwardly from the terminal lines of its bearing surface toward its vertical, diametric plane, and having an intermediate, joining, reversed-curved surface of the same radius, whereby the side of 110 120 125 130

one element may bear against the proximate side of the adjacent element through a rocking movement through the full angle determined by the length of their bearing surfaces and spring controlled followers located in each end of the casing and engaged with the end rockers.

8. In an antifriction bearing comprising a casing, a plurality of closely spaced anti-friction rockers located in said casing and having top and bottom bearing surfaces adapted to permit a rocking movement through a predetermined angle, means providing interacting bearing parts between the adjacent sides of said rocking elements whereby said elements are permitted to rock together through substantially the full amount of their predetermined angle of rocking movement, the end rocking elements each being provided on the side adjacent the end of the casing with an extension having a flat bearing surface tangential to the bearing surface of said element.

9. An antifriction bearing comprising a casing, a plurality of closely spaced rockers located in said casing and having top and

bottom bearing surfaces adapted to permit rocking movement through a predetermined angle, each of said rockers having that side which is adjacent to the next rocker, curved inwardly from the terminal lines of its bearing surface toward its vertical, diametric plane, and having an intermediate, joining, reversed-curved surface of the same radius, whereby the side of one element bears against the proximate side of the adjacent element throughout substantially the full rocking movement of said elements and acts to stop the further movement of said element when the same has been rocked through its predetermined limit of movement, and spring controlled followers located in each end of the casing and engaged with the end rockers.

In testimony that I claim the foregoing as my invention I affix my signature in the presence of two witnesses, this 21st day of May.

ARNOLD A. WEIGEL.
